Application January 18, 1934, Serial No. 707,168

2 Claims. (Cl. 35—9)

This invention aims to provide novel means whereby exercises used in connection with teaching may be preserved and be made accessible at any time for use.

5 It is within the province of the disclosure to improve generally and to enhance the utility of devices of that type to which the invention appertains.

With the above and other objects in view, 10 which will appear as the description proceeds, the invention resides in the combination and arrangement of parts and in the details of construction hereinafter described and claimed, it being understood that changes in the precise embodiment of the invention herein disclosed, may 15 be made within the scope of what is claimed, without departing from the spirit of the invention.

In the accompanying drawings:

20 Fig. 1 shows in front elevation, a device constructed in accordance with the invention, the doors being opened;

Fig. 2 is a rear elevation wherein the entire middle portion of the device as an entirety is 25 represented as having been broken out;

Fig. 3 is an end elevation;

Fig. 4 is a vertical section on the line 4—4 of 30 of Fig. 2;

Fig. 5 is a fragmental vertical section showing 35 the pawl and ratchet mechanisms;

Fig. 6 is an elevation showing one of the pawl and ratchet mechanisms;

Fig. 7 is a fragmentary sectional view showing 40 the connecting means between the fly sheet and the record strips.

In carrying out the invention there is provided a support, which may be a cabinet 1, open at the back, as shown in Fig. 2. The front of the cabinet 1 may be closed by foldable, horizontally swinging doors 2, hinged at 70 to the ends 20 and 21 of the cabinet, the doors being made up of sections which are connected together by hinges 80. In the bottom of the cabinet 1 there are drawers 3 for storing writing and printing materials, and the like. On its inner side, one part of one of the doors may be equipped with a chart 4 for use in teaching music. The chart 4 may be of any desired kind, and there may be as many of these charts as the area of the doors will permit. To facilitate the drawing of lines on the record strips 26 (hereinafter described), the cabinet 1 is provided at its ends and at its forward side with vertical scales 5, shown in Fig. 1.

55 Cleats 7 connect a vertical backing plate 6

with the ends 20 and 21 of the cabinet 1. An idle roll 8 is journaled on the ends 20 and 21 of the cabinet 1 and is located above the backing plate 6, as shown in Fig. 4. On the end 21 of the cabinet 1 there is a vertical bearing 9 having upwardly extended slots 18 shown in Fig. 4.

One end of a receiving roll 10 is journaled in the bearing 9 and in the end 20 of the cabinet 1. Adjacent to the end 20 of the cabinet 1, the shaft 11, which carries the receiving roll 10, is provided with a ratchet wheel 14 adapted to be engaged by a pawl 12, pivoted to the end 20 of the cabinet 1. Second rolls 15 are provided, and are arranged in a vertical plane, behind the backing plate 6. The second rolls 15 are carried by shafts 16. The shafts 16 are journaled in the end 20 of the cabinet, and in the slots 18 of the bearing 9. Any one of the shafts 16, therefore, may be removed at will. Pawl and ratchet mechanisms 17, of the kind hereinbefore described, control the rotation of the shafts 16 and the second rolls 15. An operating device 19 such as a crank, is provided. The crank is assembled detachably with the exposed ends of any of the shafts 16 or 11, by threading or otherwise.

Second idle rolls 22 are located in a vertical plane beneath the backing plate 6, as shown in Fig. 4. The idle rolls 22 have their ends journaled in bearings 30 on the ends 20 and 21 of the cabinet 1. A flexible fly sheet 23 is wound about the receiving roll 10. The sheet 23 passes upwardly, and then downwardly, about the idle roll 8, the free end of the sheet 23 being disposed in front of the backing plate 6. On the lower edge of the sheet 23 there is a binder 24, shown in Fig. 7. The binder 24 carries one member 25 of a detachable connection, which may be a snap fastener. Flexible record strips 26 are wound about the second rolls 15. The record strips 26 extend downwardly and then upwardly, about the respective second idle rolls 22, the ends of the record strips 26 being disposed in front of the backing plate 6. On their upper edges, the record strips 26 have binders 27, shown in Fig. 7. The binders carry members 28 of separable connections, such as snap fasteners. The parts 28 of the record strips 26 are adapted to be connected, one at the time, with the fasteners 25 of the sheet 23. Detachable handles 29 are provided, and are adapted to be connected with the rear ends of the detachable connections 28 on the record strips 26. Snap fasteners preferably are used for the mounting of the handles 29.

In practical operation, the handles 29 are assembled with the fasteners 28 of the record strips 26, as shown in Fig. 1. Figure 4 shows that the handles 29 on the record strips 26 are thick enough so that they cannot pass between the lower or second idle rolls 22. The end of each record strip, therefore, is available at all times. The operator pulls out the lower end of the record strip 26 by means of the corresponding handle 29. The handle 29 is removed from the fastener 28 of the record strip 26. The fasteners 28 of the record strip 26 then are connected to the fasteners 25 of the sheet 23. If the crank 19 is assembled with the shaft 11 of the receiving roll 10, the sheet 23 may be reeled on the roll 10, the corresponding record strip 26 being raised in front of the backing plate 6, as shown in Fig. 1. The exercise then may be written on the exposed part of the record strip 26. The operator can shift the crank 19 to the shaft 16 of the roll 15 that carries the record strip 26 which has been used, and the record strip may be wound up again on the corresponding roll 15. Another record strip 26 may be operated in the same way. Examples or exercises in four or more subjects thus may be made available. The exercises or examples are preserved for review or for other purposes, because they are on the record strips 26, which, when not in use, are wound on the rolls 15. All of the sheet 23, and as much of any record strip 26 as is desired may be wound about the roll 10 so as to expose any of the exercises or examples which have been inscribed on the exposed portion of the record strip 26.

The device is simple in construction, but it affords a means whereby exercises previously used may be made available, the construction having obvious advantages over the practice of chalking an exercise on a blackboard, erasing the exercise, and then writing it over, in the event of review. The device, moreover, affords a means whereby

classes in different subjects may be taught successively.

Having thus described the invention, what is claimed is:

1. In a device for preserving and filing school exercises and the like, a support, a backing plate carried by the support, a plurality of idlers on the support at the lower end of the backing plate, a first receiving roll journaled on the support to the rear of the backing plate, second receiving rolls journaled on the support to the rear of the backing plate, means for rotating any one of the receiving rolls, a sheet wound about the first receiving roll and extended upwardly, and then downwardly in front of the backing plate, record strips wound about the second receiving rolls, the record strips extending about the idlers, and means for connecting the exposed end of any record strip detachably with the exposed end of the sheet. 5 10 15 20

2. In a device for preserving and filing school exercises and the like, a support, a backing plate carried by the support, a plurality of idlers on the support at the lower end of the backing plate, a first receiving roll journaled on the support to the rear of the backing plate, second receiving rolls journaled on the support to the rear of the backing plate, means for rotating any one of the receiving rolls, a sheet wound about the first receiving roll and extended upwardly, and then downwardly in front of the backing plate, record strips wound about the second receiving rolls, separable fastener parts joining the exposed end of any record strip with the exposed end of the sheet, and a handle detachably assembled with the fastener parts of any record strip and removable to enable the end of any record strip to be detachably assembled with the exposed end of the sheet, by means of the fastener parts of said record strip and of the sheet, the handles being of such thickness that they cannot pass backwardly between the idlers. 25 30 35 40 45
